UNITED STATES PATENT OFFICE.

GEORGE E. DUNTON, OF NEW YORK, N. Y.

APPARATUS FOR APPLYING A CONDUCTIVE COATING TO THE SURFACE OF A MOLD USED IN THE ART OF ELECTROTYPEING.

1,111,442.

Specification of Letters Patent. Patented Sept. 22, 1914.

Application filed December 17, 1912. Serial No. 737,281.

To all whom it may concern:

Be it known that I, GEORGE E. DUNTON, residing at New York city, county of New York, State of New York, a citizen of the 5 United States, have invented certain new and useful Improvements in Apparatus for Applying a Conductive Coating to the Surface of a Mold Used in the Art of Electrotyping; and I do hereby declare the following to be a full, clear, and exact description of the invention, such as will enable others skilled in the art to which it pertains to make and use the same.

My invention relates to improvements in 15 apparatus for applying a conductive coating to the surface of a mold used in the art of electrotyping.

In producing printing plates by the electrotype process the wax mold is made by 20 pouring melted wax or other suitable molding material over thin sheets of metal and allowing the wax to cool and after becoming sufficiently hard the surface of the mold is shaved off until it presents a perfectly 25 smooth even surface when the form containing the impression of the printing plate, desired to be produced, is pressed into this surface, the form removed and the mold trimmed by means of a heated knife which 30 removes the more elevated portions and gives uniformity to the indentations which in the plate will be the reverse of the elevations in the mold, and any grease, oil or oily substance which may have been expressed from the mold, by the pressure of 35 the form, is also removed. A coating of conductive material, such as liquid graphite, is then applied to the mold surface in order that it shall become conductive to 40 electricity and exercise the function of the cathode element in the electrolytic bath wherein it is to receive the predetermined deposit of metal. Prior to its immersion in the electrolytic bath, and following the administration of the conductive coating, the 45 mold is treated to a preliminary coating or to a deposit of copper or other suitable metal through the agency of or by chemical means; the mold is then thoroughly rinsed 50 or washed off, with a powerful spray or jets of water, and the surface is flowed with a solution of sulfate of copper, fine iron dust is sprinkled over the surface of the copper which is gently agitated by means of 55 a suitable brush, and by the chemical action

which follows the iron enters into the solution in the form of a sulfate and the copper is displaced appearing as a precipitate of the metal on the conductive coated surface of the mold, the mold is then rinsed 60 off with water and hung in the plating bath to receive the desired deposit of metal and when this deposit of metal becomes of the desired thickness the mold is removed from the bath and the shell stripped off from 65 the same after which it receives the proper backing and is finished for the printing machine upon which it is desired to be used. It is not necessary to describe the subsequent operations which follow the deposition of the electrotype shell, as my invention relates particularly to an apparatus for the treatment of the surface of the mold with the conductive coating prior to the deposition of the metal in the electrolytic 70 bath. As the degree of perfection of the printing surface of the electrotype plate depends on the manner in which the conductive coating is applied to the surface of the mold it is of the utmost importance that the 75 coating should be applied and distributed smoothly and evenly and made to absolutely cover the entire surface of the mold and the indentations therein and not leave any portions of the same uncovered or any im- 80 perfections.

The object of my invention is to provide an apparatus which will apply the conductive coating evenly and smoothly to the entire surface of the mold and the indentations, projections, &c., in or on its surface and thereby provide for the production of 85 a perfect printing surface on the electrotype plate produced therefrom.

A further object is to provide means for 90 applying the conductive coating to a mold, preferably having a surface provided with indentations, but which may have projections on its surface or any other character of surface and which can be flat, curved 95 or any other desired shape or contour.

A further object is to provide means for 100 applying a conductive coating to the surface of a mold and to the indentations in its surface by projecting the said conductive 105 coating into the indentations and onto the surface of the mold simultaneously at different angles.

A further object is to provide means for 110 applying a conductive coating to the sur-

face of a mold and to the indentations in its surface by projecting the said conductive coating into the indentations at different angles before the conductive coating drops, by force of gravity, from the surface of the mold.

10 A further object is to provide means for applying a conductive coating to an inverted mold, said means being above the surface of the body of the conductive coating in the receptacle containing the same.

15 A further object is to provide means for rotating the mold and means for applying a conductive coating to the entire surface of the walls of the indentations.

15 A further object is to provide a rotatable and reciprocatory mold.

20 A further object is to provide means for rotating the mold while applying the conductive coating to its surface.

25 A further object is to provide means for applying a conductive coating to the surface of a mold and the indentations therein by means of a rotatable mold and a rotatable and reciprocatory cylinder having means for projecting the coating therefrom.

30 A further object is to provide means for rotating and reciprocating the means for projecting a conductive coating onto the mold.

35 A further object is to provide means for applying a conductive coating to the indentations in a mold and means for presenting different portions of said indentations to the action of the conductive coating.

40 A final object is to provide an apparatus for the purpose set forth which is simple, inexpensive and durable in construction and easy and effective in operation.

45 Referring to the drawings:—Figure 1 is a longitudinal sectional view partly in elevation. Fig. 2 a top plan view partly in section. Fig. 3 a sectional end view partly in elevation. Fig. 4 a detail top plan view of the mold carriage. Fig. 5 a detail sectional view of one of the mold clamping devices. Fig. 6 a plan view of one of the mold clamping devices. Fig. 7 a fragmentary sectional view of the mold turn table and its operating mechanism. Fig. 8 a top plan view of the pawl and ratchet device of the mold turn table. Fig. 9 a fragmentary plan view showing the mold carriage, turn table and operating parts. Figs. 10 to 15 inclusive are dia-

55 grammatic views showing the various positions which the molds assume in applying the conductive coating. Fig. 16 a fragmentary sectional view of the mold and the conductive coating projecting and distributing means. Fig. 17 a detail plan view of the rotatable and reciprocatory cylinder, T-heads and guides. Fig. 18 a top plan view of a modified form of the rotatable and reciprocatory cylinder.

60 65 In the drawings in which like reference

70 characters denote like parts throughout the several views, 1 represents a suitable tank, receptacle or container for the conductive coating of graphite of my apparatus, made preferably of wood lined with sheet metal but which may be made of any other suitable material, which is supported by means of legs 2 and provided with front and rear end walls 3 and 4, respectively, side walls 5 and 6, a bottom 7 slanting downward to the rear wall 4, and a top 8 having a hinged cover 9 with any suitable catch to keep it closed and a handle 10.

75 80 85 90 95 100 105 110 115 120 125 130 The means for scraping up any graphite or other conductive coating which precipitates to the bottom of the tank, mixing the graphite and feeding it to the mixing means comprises;—an endless sprocket chain conveyer 11 having a series of scrapers 12, preferably made of heavy sheet rubber, and mounted on sprocket wheels 13 on shafts 14 which extend transversely across the tank 1 and have their ends mounted in suitable bearings in the side walls 5 and 6 thereof, 15 being a mixing drum or cylinder mounted on shaft 16 extending transversely across the tank 1 and having its ends mounted in bearings in the side walls 5 and 6 of said tank and its front end extending through the side 6 of the tank, and 18 a sprocket chain operatively connecting sprocket 19 on shaft 14 of the conveyer 11 with sprocket 20 on the shaft 16 of the mixing drum or cylinder. The upper portion of the mixing drum or cylinder is inclosed by a curved cover 21 which extends across the tank transversely and is secured to the rear end wall 4 thereof by means of brackets 22. The means for withdrawing or exhausting the conductive coating of graphite or other suitable material, circulating the same and projecting it against the mold comprises, a pump 23, preferably of the rotary turbine type but may be any suitable liquid forcing device which will accomplish the desired results in a satisfactory manner. The pump 23 is connected to and communicates with the tank 1 by means of a short curved pipe 24, by which the conductive coating is withdrawn or exhausted from said tank, and the outlet pipe 25 of the pump is connected to a vertical pipe 26 the upper end of which connects with a horizontal pipe 27 the opposite ends of which are connected to short horizontal pipes 28 which pass through the upper portion of the rear wall 4 into the tank while the lower end of the pipe 26 is connected to a pipe 29 which extends diagonally under the bottom of the tank and connects with a vertical pipe 30 rising in front of the tank and said pipe 30 connects with a horizontal pipe 31 the opposite ends of which are connected to short horizontal pipes 32 which pass through the upper portion of the front wall 3 into the tank.

The conductive coating or graphite projector consists of a rotatable cylinder or barrel 33 having a double row of holes 34 and 35 through which the conductive coating is forced as it is projected against the surface of the mold, said holes are preferably spaced apart at an angle of forty-five degrees, but they may be spaced apart at any desired angle, and said cylinder or barrel being pivotally mounted in bearings 36 in the T-shaped castings 37 on each side of the slidable frame 38, said castings being connected by means of a bar 38^a secured to the under portions of the same and each 15 having hollow guides 39 and 40 projecting therefrom which are slidably mounted in the short horizontal pipes 28 and 32, respectively. Suitable packing is provided to insure air and liquid tight joints between the 20 hollow guides and the short horizontal pipes 28 and 32. One end of the cylinder or barrel 33 is provided with an upwardly projecting pin or lug 40^a and rollers 41 and 42 are mounted on spring arms 43 which in 25 turn are secured to the T-shaped castings in proximity to the side 6 of the tank 1.

44 and 45 are reversing arms pivoted to the side wall 6 of the tank, 46 being levers also pivoted to the side wall 6 of the tank, 30 one end of each of which is connected to one of the reversing arms by means of a rod 45^a while the opposite end is connected to a rod 47 slidably mounted in a bracket 48 and provided with a spiral spring 49, which 35 surrounds the same, for retaining said rod 45^a normally in its outward position and 50 are nuts adjustable on said rods for regulating the tension of the spiral springs 49. The rotatable cylinder or barrel 33 is rotated 40 in one direction, viz., forwardly, by the reversing arm 44 engaging the roller 41 and then slipping off the same, under tension of the spring 49 on rod 47 at the rear of the tank, and striking the pin or lug 40^a and 45 throwing it forwardly and the rotatable cylinder or barrel is rotated in the opposite direction, viz., rearwardly, by the reversing arm 45 engaging the roller 42 and then slipping off the same, under tension of the spiral 50 spring 49 on rod 47 at the front of the tank, and striking the pin or lug 40^a and throwing it rearwardly. The slidable frame 38 and the cylinder or barrel 33, pivoted therein, are reciprocated by means of an internally screw threaded sleeve 51 connected to the bar 38^a of the slidable frame 38 by means of a link 52, said sleeve being mounted and adapted to move on the right hand screw threads 53 of the driving shaft 54 which 55 has right and left hand screw threads, 53 and 55, respectively, said shaft 54 being mounted in tubular bearings 56 in the front and rear end walls of the tank, the rear end of the shaft 54 extending through the 60 rear end wall of the tank and being mounted

in a bearing 57 formed in a bracket 58 bolted to the outer face of the said rear end wall. The mold carriage 59 consists of an open frame 60 with axles having small wheels 64, designed to travel between the tracks 61 70 secured to the side walls 5 and 6 of the tank, inwardly projecting ledges 65 and a plate 66 hinged at one end thereof.

A turn table 67 is pivoted to the underside of the plate 66 by means of a screw bolt 68 having a nut 69 and 70 is a sleeve mounted on said screw bolt having a ratchet 71 secured to its lower end and 72 and 73 are annular rings placed between the plate 66 and the turn table 67, the ring 72 being 80 securely attached to the plate 66 and the ring 73 being securely attached to the turn table.

74 are spring controlled pins mounted in the plate 66 and the annular ring 72 which engage holes or depressions 75, 76, 77 and 78 in the annular ring 73 with which said pins are designed to register for the purpose of holding the turn table in its various positions when applying the conductive coating, and a spring controlled pawl 79 is provided which is mounted on a screw 80 secured in the turn table 67 and engages the ratchet 71 which prevents the turn table from turning backward.

Clamping devices 81, for securing the mold 82 to the turn table, are provided having bolts 83 passing through slots 84 of the turn table and having heads 85 and eyes 86, wedge shaped, washers 87 mounted on the bolts 83 below the turn table, plates 88 with serrated edges mounted on the bolts 83 above the turn table and resting thereon and cam or eccentric levers 89 pivoted on short shafts 90 mounted in the eyes 86. The hinged plate 66 is provided with a central circular projection or hub 91 which surrounds the sleeve 70 and a cog wheel 92 is keyed to the sleeve 70 just above this circular projection 91.

Bars 92^a and 93 are slidably mounted in guides 94 projecting from the top of the hinged plate 66 and each is provided with a series of teeth 96 which mesh with the cog wheel 92. When the mold carriage 59 moves to the forward end of the tank on its first trip the end 91^a of bar 92^a will contact with the front end wall of the tank which will cause said bar to slide rearwardly and by means of the teeth 96 and cog wheel 92 the turn table 67 will be rotated to the right, one fourth of a revolution. When the mold carriage 59 moves toward the rear end of the tank, the end 97^a of the bar 93 will contact with the rear end wall of the tank, which will cause the said bar to slide forwardly and by means of the teeth 96 and cog wheel 92 the turn table 67 will be again rotated to the right, another one-fourth of a revolution. The bars 92^a and 93 are returned to their normal positions by means of spiral 110

95

100

105

110

115

120

125

130

springs 98' attached to said bars and the plate 66. By repeating this back and forth movement, the turn table will be rotated entirely around, each time the mold carriage makes four trips, and will present all sides of the mold and the indentations therein, to the action of the stream or jet of graphite projected thereon by means of the rotatable cylinder or barrel 33. The mold carriage is reciprocated by means of an internally screwthreaded sleeve 99, mounted on the left hand screwthread 55 of the driving shaft 54 and connected to the carriage by means of an upwardly extending arm or bracket 100. The rear end of the driving shaft 54 is provided with two bevel gears 101 and 102, rotatable freely thereon, which are provided with right and left hand projections, respectively, and a clutch sleeve 103 is slidably mounted on and keyed to said shaft 54 and is provided with right and left hand projections, one end having a right hand projection and the other end having a left hand projection. The sleeve 103 is provided with a rod 104 having adjustable stops 105 and 106 thereon and as the mold carriage 59 moves rearwardly, it engages the adjustable stop 105 which causes the sleeve 103, by means of the rod 104, to be disengaged from the bevel gear 102 and engage it with the bevel gear 101 and reverses the direction of rotation of the driving shaft and as the mold carriage moves forwardly it engages the adjustable stop 106 which causes the sleeve 103, by means of the rod 104, to be disengaged from the bevel gear 101 and engages it with the bevel gear 102 and again reverses the direction of rotation of the driving shaft. 107 is a shaft mounted in the bracket 58 and one end of which is provided with a bevel gear 108 fast thereon, which is designed to drive alternately the bevel gears 101 and 102 and the opposite end is provided with a pulley 109 which is operatively connected with a pulley 110 on the pump shaft 111 by means of a belt 112. The outer end of the pump shaft is provided with a pulley 113 and the outer end 50 of the shaft 16 of the mixing drum is provided with a pulley 114 which is operatively connected to the pulley 113 by means of a belt 115. A driving pulley 116 is mounted on the pump shaft 110 and is designed to be connected by means of a shaft with an engine, motor or other motive power.

The operation of the apparatus is as follows:—The mold carriage having been brought into a position at the extreme front of the tank and directly under the cover 9 thereof, the cover is opened and a sufficient quantity of graphite, previously mixed with water until it has acquired the proper consistency such, for instance, as of paste,

cream or syrup, is poured into the tank until it is about one quarter or one third full or at least deep enough to entirely submerge the endless sprocket chain conveyor 11 but not of sufficient depth to touch 70 or submerge the driving shaft 54. The plate 66 of the mold carriage is raised to a vertical position, and the turn table being mounted thereon is also raised, a wax mold which has preferably been treated to remove any grease, oil or oily substance is then attached to the underside of the turn table by means of the clamping devices 81, the plate 66 is then lowered until it rests on the ledges of the mold carriage, carrying 80 with it the turn table and mold with the mold with its face downward and is locked in place by means of a suitable catch, and the cover 9 of the tank is closed. The mold carriage, as has been previously stated, being designed to be started from the front of the tank and the rod 104 being moved forward thereby will cause the clutch sleeve 103 to engage the gear 102, the rotatable cylinder or barrel 33 will be in the position 85 it assumes when turned to the right toward the front of the tank and the slidable frame 38 will be in its rearward position. The pump is then started by communicating power to the driving pulley 116 on pump shaft 110, the mixing drum, and endless sprocket chain conveyor and operated through the medium of the pulley 113, the pulley 114 and belt 115. The suction produced by the pump, causes the liquid 90 graphite or other conductive coating, which has been thoroughly stirred or mixed by the mixing drum or cylinder 15, to be withdrawn from the tank through the pipe 24 and forced, through the series of pipes 25, 105 26, 28, 29, 30, 31 and 32 and through the hollow guides 39 and 40 of the slidable frame 38 into the opposite ends of the rotatable cylinder or barrel 33 and through the double rows of holes 34 and 35 and projected upwardly against the surface of the mold and the indentations therein, the row of holes 34 projecting the conductive coating vertically and the row of holes 35 projecting the conductive coating at an angle 110 of forty five degrees. The surplus conductive coating that does not adhere to the mold drops back into the tank by force of gravity 115 and is again stirred and mixed and used over again. As the apparatus operates the mold carriage and mold move in the opposite direction from the slidable frame 38, by reason of the right and left hand screw portions on the drive shaft which is turning from right to left, and the rotatable 120 cylinder carried thereby, that is to say, as the mold carriage moves toward the rear of the tank, the slidable frame moves toward the front of the tank so that the conductive coating of graphite is applied from 125 130

the rear to the front of the mold. As the mold carriage and mold move toward the rear of the tank and just before they reach the reversing point, the slidable frame having moved toward the front of the tank, the reversing arm 45 contacts with the pin or lug 40^a on the rotatable cylinder or barrel and turns it axially rearwardly, which starts the application of the conductive coating of graphite from the front to the rear of the mold and when the operation is reversed, the arm 46 contacts with the pin or lug 40^a on the rotatable cylinder or barrel and turns it axially forwardly, which starts the application of the conductive coating of graphite from the rear to front of the mold. As has been previously stated, the direction of movement of the mold carriage and mold and the slidable frame 38 are accomplished by the reversal of the turning movement of the drive shaft 54. The direction of movement of said shaft is accomplished by the engagement and disengagement of the clutch sleeve 104 with the bevel gears 101 and 102, said sleeve being operated with the stops 105 and 106 and sliding the rod 104 backward or forward.

To illustrate the various positions that the mold is caused to assume, in applying the conductive coating to all sides of the indentations of the mold and its face, I have lettered the sides of the mold A, B, C and D. As the mold marked A will be in front in the direction of travel and the conductive coating will be projected against the side of the mold marked C, and against the side of the indentations on that side, see Fig. 10, and the operation will continue as shown in the following figures, viz., 11, 12, 13, 14 and 15.

In Figs. 10, 11, 12, and 13 the mold makes a quarter turn at each single trip of the carriage both at the front and rear. In Figs. 14 and 15 the mold makes a quarter turn to each round trip of the carriage, from front to rear and back.

If found desirable, the mold carriage and mold could be held stationary and have the conductive coating projector reciprocate thereunder or the conductive coating projector could be held stationary and have the mold carriage and mold reciprocate above the same. The method is claimed in my application for patent filed January 18th, 1913 Serial No., 742868.

I do not desire to be understood as limiting myself to the specific details of construction and arrangement as herein described and illustrated, as it is manifest that variations and modifications may be made in the features of construction and arrangement in the adaptation of the device to various conditions of use without departing from the spirit and scope of my invention and improvements. I therefore reserve the right

to all such variations and modifications as properly fall within the scope of my invention and the terms of the following claims.

What I claim is:—

1. In a device of the character described, means adapted to hold an electrotype mold in an inverted position and means for applying a conductive coating upwardly in different and changing directions to the inverted surface of the mold, substantially as described. 70

2. In a device of the character described, means adapted to hold an electrotype mold in an inverted position and means for applying a conductive coating to the inverted surface of the mold and in different positions relative thereto, substantially as described. 80

3. In a device of the character described, means adapted to hold an electrotype mold in an inverted position and means for applying a conductive coating upwardly in different and changing directions to the inverted surface of the mold and in different positions relative thereto, substantially as described. 85

4. In a device of the character described, horizontally rotatable means adapted to hold an electrotype mold having indentations therein in an inverted position and means for applying a conductive coating upwardly to the indentations and inverted surface of the same, substantially as described. 95

5. In a device of the character described, a mold carriage, a mold holder mounted horizontally thereon adapted to hold a mold in an inverted position and means for applying a conductive coating upwardly to the inverted surface of the mold, substantially as described. 100

6. In a device of the character described, horizontally movable means adapted to hold an electrotype mold having indentations therein in an inverted position and movable means for applying a conductive coating to the indentations and surface of the mold, substantially as described. 110

7. In a device of the character described, a substantially horizontal reciprocating mold carriage, a rotatable mold holder thereon, means for operating said mold carriage and mold holder and means located below the mold holder for applying a conductive coating to a mold carried by said holder upwardly, in a substantially vertical direction substantially as described. 115

8. In a device of the character described, a mold carriage, an inverted movable mold holder thereon, and means for applying a conductive coating upwardly to a mold carried by said mold holder operated simultaneously, substantially as described. 125

9. In a device of the character described, a mold carriage, a rotatable mold holder, 130

- and movable means for applying a conductive coating upwardly to a mold carried by said mold holder all operated by the same means, substantially as described.
10. In a device of the character described, a reciprocatory mold carriage, an inverted horizontal mold holder rotatable thereon, means for operating said mold carriage and mold holder and movable means under the mold holder for applying a conductive coating to a mold carried by the holder, substantially as described.
11. In a device of the character described, a mold carriage, an inverted rotatable mold holder thereon and means for applying a conductive coating to a mold carried by the holder all operated by the same means, substantially as described.
12. In a device of the character described, a reciprocatory mold carriage, adapted to carry an inverted rotatable mold thereon and reciprocatory and rotatable means for applying a conductive coating to the mold, substantially as described.
13. In a device of the character described, a reciprocatory mold carriage, adapted to carry an inverted rotatable mold thereon and a reciprocatory rotatable conductive coating cylinder projector having rows of holes therein, one row being at an angle to the other, substantially as described.
14. In a device of the character described, a reciprocatory mold carriage, adapted to carry an inverted rotatable mold thereon, a reciprocatory cylinder provided with holes and means for supplying said cylinder with a conductive coating and projecting said coating through the holes therein onto the surface and indentations of the inverted mold, substantially as described.
15. In a device of the character described, an inverted rotatable mold holder adapted to carry a mold, a movable cylinder under said mold and holder provided with rows of radially arranged holes and means for supplying said cylinder with a conductive coating and projecting said coating through said holes upwardly onto the surface and indentations of the mold, substantially as described.
16. In a device of the character described, an inverted movable mold, rotatable means for supporting said mold, a cylinder under said mold provided with rows of radially arranged holes and means for supplying said cylinder with a conductive coating and projecting said coating through said holes upwardly onto the surface and indentations of the mold, substantially as described.
17. In a device of the character described, an inverted movable mold holder and a cylinder movable simultaneously therewith, holes in said cylinder and means for supplying said cylinder with a conductive coating and projecting said coating through the said
- holes onto the surface and indentations of a mold, carried by said mold holder, substantially as described.
18. In a device of the character described, an inverted movable mold holder adapted to carry a mold, rotatable means for applying a conductive coating upwardly thereto and means for rotating said mold holder to present each side of the mold in turn to the action of the conductive coating, substantially as described.
19. In a device of the character described, a substantially horizontal mold holder adapted to carry a mold, rotatable means for applying a conductive coating to the mold upwardly in a substantially vertical direction and means for rotating said mold to present each side of the indentations of the mold in turn to the action of the conductive coating, substantially as described.
20. In a device of the character described, a driving shaft having right and left hand screwthreaded portions, a mold carriage having a mold holder and operatively connected to one of said screwthreaded portions and a conductive coating projector operatively connected to the other screwthreaded portion and means for rotating said driving shaft, substantially as described.
21. In a device of the character described, an inverted movable mold holder adapted to carry a mold provided with indentations, movable means for applying a conductive coating to the walls of the indentations and means for rotating the inverted mold holder and presenting the several sides of the indentations of the mold successively to the action of the conductive coating, substantially as described.
22. In a device of the character described, a mold carriage adapted to carry an inverted mold thereon, a slidable frame having a cylinder with holes, means for supplying said cylinder with a conductive coating and projecting the same through the said holes onto the mold, a drive shaft operatively connected to said mold carriage and the slidable frame, means on the mold carriage for reversing the direction of rotation of the drive shaft, means for rotating said cylinder, and means for turning said mold, substantially as described.
23. In a device of the character described, a tank having a conductive coating therein, rotary mixing means for said conductive coating, a mold carriage having an inverted rotary mold holder adapted to carry a mold, a cylinder having holes, means for withdrawing the conductive coating from the tank and supplying it to the cylinder and means above the surface of the conductive coating in the tank for projecting it through the holes therein onto the mold, substantially as described.
24. In a device of the character described,

a tank having a conductive coating therein, rotary mixing means for said conductive coating, means for feeding said mixing means, an inverted movable mold holder 5 adapted to carry a mold, a conductive coating projector under said mold above the surface of the conductive coating in the tank and means for withdrawing the conductive coating from said tank and supplying 10 it to the projector and projecting it upwardly onto the mold, substantially as described.

25. In a device of the character described, an inverted mold holder adapted to carry a 15 mold, a system of pipes, a frame slidable in the ends of said pipes, a cylinder having holes and rotatably mounted in said frame and means for supplying a conductive coating to said cylinder and projecting it 20 through said holes onto the mold, substantially as described.

26. In a device of the character described, a tank having a conductive coating therein, a mold carriage having a turntable adapted 25 to carry an inverted mold, a system of pipes connected to said tank, a frame slidably mounted in the ends of said pipes, means for sliding said frame, a perforated rotatable cylinder mounted in said frame and 30 means for rotating the same, and means for withdrawing the conductive coating from the tank, supplying it to the rotatable cylinder and projecting it through the perforations of the same onto the mold, substan- 35 tially as described.

27. In a device of the character described, a drive shaft having right and left hand

screwthreaded portions, means for rotating said shaft, a reciprocating mold carriage operatively connected to one of the screw-threaded portions of the drive shaft and provided with a turntable adapted to carry an inverted rotatable mold, means for rotating said mold, a rotatable and reciprocatable perforated cylinder under said inverted mold operatively connected to the other screwthreaded portion of the drive shaft, means for rotating said cylinder, means for reversing the direction of rotation of said drive shaft and means for supplying a conductive coating to said cylinder and projecting it through the perforations therein onto the mold, substantially as described. 40 45 50

28. In a device of the character described, 55 a drive shaft, a mold carriage operatively connected to the same and provided with a rotatable turn table adapted to carry a mold, a movable perforated cylinder operatively connected to the drive shaft, means for supplying a conductive coating to the said perforated cylinder and projecting it through 60 said perforations onto the mold, means for rotating the turn table and mold at each end or limit of travel of the mold carriage and 65 means for rotating the perforated cylinder, substantially as described.

In testimony whereof, I affix my signature in the presence of two witnesses.

GEORGE E. DUNTON.

Witnesses:

HENRY W. BECKER,
NETTIE F. FAIRCHILD.
